[57] CLAIM

The ornamental design for a watch, as shown and described.

DESCRIPTION

FIG. 1 is a perspective view of my design; FIG. 2 is a top plan view thereof; FIG. 3 is a left side elevational view thereof; FIG. 4 is a front elevational view thereof; and, FIG. 5 is a rear elevational view thereof. The bottom of the watch forms no part of the claimed design. The right side elevational view is a mirror image of the left side.
